EMILE MOREL, OF DOMENE, FRANCE

MAGNETO-ELECTRIC MACHINE

Application filed November 7, 1928, Serial No. 317,829, and in France and Germany November 8, 1927.

This invention relates to magneto electric machines suitable for use with internal combustion engines and has for its principal object to provide a magneto of simple construction small bulk and great power. The problem of bulk has become in practice one of considerable difficulty to solve without other disadvantages since engine designers have fixed very limited standard maximum dimensions for magneto mountings on engines.

The employment of so-called inductor magnetos i. e. magnetos with rotating magnet systems has assisted towards finding a satisfactory solution to the problem and the appearance of magnetic steels such as cobalt steel of high coercive force and high remanence has still further assisted matters.

Nevertheless, despite these advances known magnetos are still not sufficiently powerful and stable if of small size.

In one arrangement in accordance with the present invention the magnet system is constructed of steel such as cobalt steel having a high coercive force and high remanence, for example, in the form of a ring having diametrically opposed polarities which may be mounted on a bronze spindle and is provided with two associated polar masses of soft steel. The polar masses, which may be solid or laminated, are in the form of portions of a ring comprising each an angle of about 90 degrees and are positioned on the outer surface of the magnet ring opposite the magnetic poles thereof.

This arrangement, however, is only fully satisfactory in certain cases, and although it is a considerable improvement on known arrangements it only provides a complete solution to the problem for magnetos in which the ratio of the internal diameter to the external diameter of the annular magnet lies within certain limits outside which the magnetic flux tends to be manifested towards the interior of the magnet ring. The fall in intensity of magnetic field becomes considerably important when the magnet is located and rotated in an induction electromagnetic circuit, and moreover the stability of the magnet is sometimes not as good as it might be.

The conditions which a satisfactory induc-

tive ring magnet must fulfill are that it must have a magnetic field as intense as possible both on open and closed circuit, the said field must be distributed as far as possible on the exterior of the magnet, the fall in field intensity must be as small as possible when the ring is, after magnetization, located and rotated in an induction electromagnetic circuit, and the magnet must be stable both as regards direction and intensity of magnetic field. In addition, of course the magnet should be of simple and robust construction.

It has now been found, as the result of experiment, that the fall in intensity of magnetic field increases with increase in the number of parasitic lines of force within the magnet ring while lack of stability in the magnet is caused to a large degree by variations in intensity and direction of such parasitic lines. Further, stability is increased when the number of parasitic lines is diminished or (even when no such diminution is effected) when their direction is fixed.

In another arrangement in accordance with the invention the bronze spindle on which the annular magnet is mounted is replaced by a core of soft iron or steel, the presence of which stabilizes the interior lines of force of the ring and thereby diminishes the fall in intensity of the magnetic field when the magnetized ring operates as an inductor in an electromagnetic circuit and stabilizes the magnet. Further its employment simplifies the construction of the rotating magnet and renders it most robust and of a lower cost.

The polar masses of the magnet may be provided with solid or laminated projections of metal similar to that of the masses themselves and attached thereto or formed as prolongations thereof, said projections enclosing the magnetized ring at a short distance therefrom. The extremities of the prolongations should face one another without touching in the neighbourhood of the neutral line of the polarities of the magnet. The said projections assure a better distribution of the flux in the ring and increase the magnetic stability.

The invention is illustrated in the accompanying drawings in which

Figure 1 is a side view of one form of construction of a magnet in accordance with the present invention;

Figure 2 is a section of this magnet shown in position in an inductor circuit;

Figure 3 is a section on line A—A of Figure 4 of a modified magnet; and

Figure 4 is a side view of Figure 3.

- Referring to Figures 1 and 2 the rotating magnet of an inductor type magneto comprises a ring 1 of steel of high coercive force and high remanence, the interior diameter of which is relatively small with respect to the exterior diameter. Within the ring is an interior core 2 of soft iron or steel in close contact with said ring and which serves as the rotating shaft of the magnet 3, 3a are polar masses formed of solid or laminated soft iron or steel, arranged closely on the exterior surface of the magnet 1 and each subtending an angle of about 90°, preferably somewhat above this figure. These polar masses which are concentric with the exterior surface of the magnetized ring 1, are fixed thereto by screws, 4, 4a, which also serve to render said polar masses solid with said ring. Obviously the screws may be replaced by a rivet passing from one polar mass to the other or by any other equivalent device.
- 30 A rotating magnet thus constituted possesses a higher magnetic power with respect to its volume and gives remarkable results of stability of field when utilized as an inductor in a customary electromagnetic circuit 5, 6, 35 5a. Owing to the fact that the ring and polar masses are in close magnetic connection the magnetic flux is substantially equally distributed over the whole of the exterior surface of said polar masses instead of decreasing towards the extremities thereof as would be the case if they were merely projections from the mass of the ring 1. The screws 4, 4a do not noticeably diminish the effectiveness of the inductor.
- 45 In the modification shown in Figures 3 and 4 the polar masses 3, 3a are prolonged circumferentially at 7, 8, 7a, 8a, these prolongations extending around portions of the periphery of the magnetized ring 1 and being spaced at a short distance therefrom and the extremities of said prolongations being opposite one another and separated by a short distance at the neutral line of the magnet polarities. These projections are, in the construction illustrated, integral with the polar masses 3, 3a, but they may, of course, be separate members attached thereto. The provision of such prolongations increases still further the stability of the magnet.

60 What I claim is:—

1. A magneto electric machine of the inductor type having an inductor comprising a magnetic ring of steel of high coercive force and remanence, a mounting core passing through said ring for rotating it, a plurality

of polar masses of soft magnetic material attached to and in magnetic contact with the periphery of said ring so as to be magnetically connected therewith, and prolongations upon said polar masses, said prolongations being spaced a short distance from said ring and partly embracing it, the extremities of the prolongations on adjacent polar masses being a small distance apart in the neighbourhood of the neutral polarities of the said ring.

2. A magneto electric machine of the inductor type having an inductor comprising a magnetic ring of steel of high coercive force and remanence having an interior diameter relatively small with respect to the exterior diameter, a mounting core passing through said ring for rotating it, a pair of polar masses of soft magnetic material attached to and in contact with the periphery of said ring so as to be magnetically connected therewith, said polar masses being arranged diametrically opposite one another and embracing each about one quarter of the circumference of said ring, and prolongations upon said polar masses, said prolongations being spaced a short distance from said ring and partly embracing it, the extremities of the prolongations on opposite polar masses being opposite one another and a small distance apart in the neighbourhood of the neutral line of the polarities of said ring.

3. A magneto electric machine of the inductor type having an inductor comprising a magnetic ring of cobalt steel of high coercive force and remanence having a diameter greater than its thickness, a mounting core of soft magnetic material passing through said ring for rotating it, and a pair of polar masses of soft magnetic material closely attached to and in magnetic contact with the periphery of said ring so as to be magnetically connected therewith, said polar masses being arranged diametrically opposite one another and embracing each about one quarter of the circumference of said ring, means extending throughout a diameter of said ring for attaching said polar masses thereto, and prolongations upon said polar masses, said prolongations being spaced a short distance from said ring and partly embracing it, the extremities of the prolongations on opposite polar masses being opposite one another and a small distance apart in the neighbourhood of the neutral line of the polarities of the said ring.

In testimony whereof I have signed this specification.

EMILE MOREL.
